UNITED STATES PATENT OFFICE.

CHARLES HALL, OF NEW YORK, N. Y., AND JOHN YOUNG, OF NEWARK, NEW JERSEY, ASSIGNEES TO SAID CHARLES HALL.

BOLT-MACHINE.

SPECIFICATION forming part of Letters Patent No. 317,642, dated May 12, 1885.

Application filed February 24, 1885. (No model.)

To all whom it may concern:

Be it known that we, CHARLES HALL, of the city and State of New York, and JOHN YOUNG, of Newark, in the county of Essex and State of New Jersey, have invented an Improvement in Bolt-Machines, of which the following is a specification.

Bolt-machines have heretofore been made in which the main shaft revolves once for each blow that is struck upon the bolt-head. In practice it is found that machines of this character cannot be driven at a high speed, because of the concussion to which the respective parts are subjected. Some of these parts are necessarily heavy, and their momentum under high rates of speed causes the parts to be broken, strained, or injured, or the smaller parts of the machine to become bent or displaced.

Our improvements are intended to obviate the aforesaid difficulties; and such improvements relate to the peculiarities of construction hereinafter described, and to the combinations of devices.

In the drawings, Figure 1 is a plan view of the bolt-machine. Fig. 2 is a side elevation with the dash-pot in section; and Fig. 3 is a vertical longitudinal section at the line *x x*, Fig. 1.

The frame A is supported on suitable legs or cross-frames, B, and C C are the pillow-blocks for the main shaft D. This shaft D is provided with fly-wheels E, and it is driven by competent power.

G is a bearing-block containing the die G', which is within a recess in said block, and secured by a bolt, g.

H is a swinging head-block, supported by a shaft, H', that passes through the cross-pieces A² A³ of the frame. The upper end of this swinging head-block is recessed for the reception of the clamping-die H², that is held in place by the screw-bolt h, and there is an arm, H³, projecting laterally from the swinging head-block and extending out over the lever K. This lever K is pivoted at k, and the moving end thereof is above the main shaft D, at which place a double cam, L, is applied to such main shaft D. The under surface of the lever K is the arc of a circle,

against which the cams L act, and there is between the lever K and the projecting arm H³ a thrust-piece with studs at opposite sides entering into recesses in the lever K and arm H³, respectively. This thrust-piece M, being 55 preferably in the form of a ring, will break and prevent injury to the other parts of the machine in case of any obstruction to the proper movements of the swinging head block H. This thrust-piece may be either straight or 60 curved. There is a link-piece, M', that connects the arm H³ and lever K. It is slotted, as shown, so that the thrust is taken entirely upon the piece M. A piston-rod, N, is connected at its upper end to the lever K, and 65 passes down to a piston in the dash-pot N', which dash-pot may be provided with jaws at its lower end, by which it is hinged to an arm that projects laterally from one of the cross-frames B; or the dash-pot may be bolted to 70 the frame and a joint be made in the piston-rod N.

At the high rate of speed at which it is advantageous to drive these bolt-heading machines, the lever K moves up and down quite 75 rapidly, and being of necessity a heavy casting the momentum and inertia are liable to produce injury to the cams and to the surface of the lever with which the cams come in contact. This dash-pot, preferably, being double acting, the 80 confined air at both the top and bottom of the stroke acts to cushion the piston and overcome the momentum and inertia of the lever K, and prevent injury or thumping of the lever. This dash-pot may be single acting, if preferred. 85

The cams L may be made as one with the shaft D, or they may be separate pieces movably connected with the shaft, so as to be removed and renewed when worn too much.

The heading-die O is secured within a stock, 90 O', supported in slides O² upon a cross-bar that rests at its ends upon the frame A. This heading-die and stock are of usual construction, and they are drawn back toward the main shaft D by a spring, P, and a rod extending to and 95 connected with such stock. At Q, upon the stock O', is a bearing-block or wearing-shoe that is adjustable, and it is secured by a bolt, q.

The main shaft D is made sufficiently broad 100 between the frames A to receive the dovetailed

bases of the cams S. These cams can be removed or replaced when worn, and they are held by screws, so to prevent end movement in the dovetailed recesses in the shaft. The 5 shaft D is below the line of the axis of the heading-die, and hence, when the cams upon the shaft D act against the shoe Q, the base or nearest part of the cam first comes into contact with such shoe, and the motion is commenced slow, 10 and the point of contact between the cams and bearing-block descends and the stroke is finished with the parts in line, or nearly so. As the shaft D is revolved rapidly these cams S act successively against the bearing-block Q 15 upon the stock O, and the heading-die is thereby reciprocated rapidly. The workman passes a highly-heated rod or bar in between the clamp or dies G' H², and these dies come up and hold said rod immediately before the heading-die O strikes a blow upon the end of the 20 rod to upset and head the same. As the jaws G' H² open the workman gives to the said rod a quarter or one-sixth of a revolution, and the heading operation is repeated until either a 25 four or a six sided head is formed between the said dies G' H².

In consequence of the shaft D being made broad between the frames and receiving the 30 separate cams S, we are able to obtain a rapid reciprocation of the heading-die with a comparatively slow rotation of the shaft D, and the cams S being separate and at some distance from each other the necessary time intervenes for the return of the heading-die between the 35 action of one cam S and the next, and the parts are not injured by the concussion or thumping action due to inertia. There is an adjustable bearing-frame T, having an inclined face adjacent to the swinging head-block H, 40 against which the said head-block presses while the heading-die strikes its blow against the bolt.

At one corner of the frame A is a projection,

U, to which is bolted a bed-shear, U', and the swinging shear-lever U² is pivoted at U³ up- 45 on one side of the frame A, and there is a cam or eccentric, U⁴, upon the shaft D, by which this shear-lever is moved, so that the workmen can cut off each bolt, after the head has been forged, by placing such bolt upon the bed-shear 50 and beneath the cutter at the end of the shear-lever.

We claim as our invention—

1. The combination, with the heading-die and its stock in a bolt-machine, of a bearing-block attached to such reciprocating stock, the shaft D, that is made broad between the supporting pillow-blocks C, and the two movable cams S, secured within recesses at opposite sides of such shaft D, substantially as set forth. 55

2. The combination, in a bolt-machine, of the swinging head-block H, having a lateral arm, H³, the lever K, pivoted to the frame A, the thrust-piece M, between the lever K and the arm H³, and the two cams L upon the shaft 65 D, acting upon the lever K, substantially as set forth.

3. In a bolt-heading machine, the combination, with the swinging head-block H, lever K, and the two cams L, of the dash-pot, a piston 70 within that dash-pot, and a rod connecting the piston to the lever K, and a hinge uniting the dash-pot to the frame, substantially as set forth.

4. The combination, with the movable head-block in a bolt-machine, of the lever to move 75 the same, the main shaft and its cam, and a dash-pot, and a connection from the piston to the lever, substantially as set forth.

Signed by us this 9th day of February, A. D. 1885.

CHAS. HALL.
JOHN YOUNG.
